(57) **CLAIM**

The ornamental design for an electrical connector as shown and described.

DESCRIPTION

FIG. 1 is a bottom, left, front perspective view of embodiment 1 of an electrical connector showing our new design; FIG. 2 is a top, right, rear perspective view of thereof; FIG. 3 is a bottom, right, front perspective view thereof; FIG. 4 is a bottom, left, front perspective view thereof; FIG. 5 is a top, right, front perspective view thereof; FIG. 6 is a top, left, front perspective view thereof; FIG. 7 is another top, left, front perspective view thereof; FIG. 8 is a top, left, rear perspective view thereof; FIG. 9 is a front elevation view thereof; FIG. 10 is a rear elevation view thereof; FIG. 11 is a bottom plan view thereof; FIG. 12 is a top plan view thereof; FIG. 13 is a right side elevation view thereof; FIG. 14 is a left side elevation view thereof; FIG. 15 is a bottom, left, front perspective view of embodiment 2 of an electrical connector showing our new design; FIG. 16 is a top, right, rear perspective view of thereof; FIG. 17 is a bottom, right, front perspective view thereof; FIG. 18 is a bottom, left, front perspective view thereof; FIG. 19 is a top, right, front perspective view thereof; FIG. 20 is a top, left, front perspective view thereof; FIG. 21 is another top, left, front perspective view thereof; FIG. 22 is a top, left, rear perspective view thereof; FIG. 23 is a front elevation view thereof; FIG. 24 is a rear elevation view thereof; FIG. 25 is a bottom plan view thereof; FIG. 26 is a top plan view thereof; FIG. 27 is a right side elevation view thereof; FIG. 28 is a left side elevation view thereof; FIG. 29 is a bottom, left, front perspective view of embodiment 3 of an electrical connector showing our new design; FIG. 30 is a top, right, rear perspective view of thereof; FIG. 31 is a bottom, right, front perspective view thereof;

(Continued)

FIG. 32 is a bottom, left, front perspective view thereof;
 FIG. 33 is a top, right, front perspective view thereof;
 FIG. 34 is a top, left, front perspective view thereof;
 FIG. 35 is another top, left, front perspective view thereof;
 FIG. 36 is a top, left, rear perspective view thereof;
 FIG. 37 is a front elevation view thereof;
 FIG. 38 is a rear elevation view thereof;
 FIG. 39 is a bottom plan view thereof;
 FIG. 40 is a top plan view thereof;
 FIG. 41 is a right side elevation view thereof; and,
 FIG. 42 is a left side elevation view thereof.

The Dash-Dash broken line portion of the figure drawings is included to show portions of the article that form no part of the claimed design. The Dash-Dot broken line portion of the figure drawings is included to show claim boundaries that form no part of the claimed design.

1 Claim, 39 Drawing Sheets
